UNITED STATES PATENT OFFICE.

CHARLES GEORGE HEAVEN, OF BIRMINGHAM, ENGLAND.

INFLATER FOR PNEUMATIC TIRES.

SPECIFICATION forming part of Letters Patent No. 591,841, dated October 19, 1897.

Application filed January 6, 1897. Serial No. 618,200. (No model.) Patented in England December 10, 1896, No. 28,239.

To all whom it may concern:

Be it known that I, CHARLES GEORGE HEAVEN, jeweler, a subject of the Queen of Great Britain, of 107 Vyse Street, Birmingham, England, have invented certain new and useful Improvements in Inflaters for Inflating Pneumatic Tires and Like Purposes, (for which I have obtained Letters Patent in England dated December 10, 1896, No. 28,239,) of which the following is a specification.

My invention has for its object improvements in inflaters for inflating pneumatic tires and like purposes by which I can more easily and expeditiously operate the same.

15 In order that my invention may be clearly understood and more easily carried into practical effect, I have appended hereunto a sheet of drawings upon which I have illustrated examples of the same.

20 Figure 1 is an elevation of my inflater in a closed position. Fig. 2 is a modification of Fig. 1, showing the plunger D extended or open. Fig. 3 is an elevation of the plunger D.

In carrying my invention into practice I 25 form the outer cylinder A with the cap a', fixed to the bottom end, and formed out of or attached to this cap are the supports or legs a², a³, and a⁴, which form a steady for the inflater when operating the same, or instead of these supports I may hinge two or 30 more pieces a⁵ to the bottom for the same purpose, as clearly shown at Fig. 2. The outlet a⁶, into which the valve connection is screwed, is formed close to the bottom. The

35 plunger or piston rod D is hollow and has two slots d' and d² formed in either side, extending nearly the bottom. The top ends d³ of these slots run at right angles to the parts d' and d² in opposite directions and are enlarged

40 at the end. I then fix the cap d⁴ on the top of this plunger and insert the coiled spring S, which is held in position by the cross-pin

S', and the usual cap is fixed to the bottom, to which the leather sucker s² is attached. This plunger is then placed into the outer 45 cylinder, and the pin s', which forms a bearing for the coiled spring, passes through two holes formed in the cap a⁷ and through the slots d' and d², as clearly shown at Fig. 2. When the plunger is forced downward, the 50 pin slides up the slots and compresses the spring, and the plunger can be held in this closed position by slightly turning it when the pin drops into the enlargements at the ends of the slots d³, as shown at Fig. 1. 55

To operate my inflater, the plunger is first released and the inflater placed upon the ground, when the plunger is pressed downward by the foot of the operator, and when the pressure is released the action of the 60 spring forces it up again, by which means the tire or other article can be easily and expeditiously inflated. Instead of actuating the plunger by the foot it may be operated by hand if desired. 65

What I claim, then, is—

In combination, the cylinder, the piston, the hollow piston-rod having the slots therein with right-angular extensions, the spring within the piston-rod and the pin passing 70 through the slots of the rod and held in the cylinder to form both a support for the spring and also a means of locking the piston and rod in closed position by engaging the angular extension of the slot, substantially as described. 75

In testimony that I claim the foregoing as my own I affix my name in the presence of two witnesses.

CHARLES GEORGE HEAVEN.

Witnesses:

THOMAS MARSLON,
GEORGE LESTER.
